UNITED STATES PATENT OFFICE.

FREDERICK H. HERHOLD, OF CHICAGO, ILLINOIS.

DESIGN FOR A STEP-LADDER CHAIR.

SPECIFICATION forming part of Design No. 23,739, dated October 23, 1891.

Application filed May 5, 1894. Serial No. 510,222. Term of patent 7 years.

To all whom it may concern:

Be it known that I, FREDERICK H. HERHOLD a citizen of the United States, residing at Chicago, county of Cook, and State of Illinois, have invented and produced a new and original Design for a Combination Step-Ladder Chair, of which the following is a specification, reference being had to the accompanying drawings, showing the essential features of the design, in which—

Figure 1, is a perspective of the article folded to the form of a chair; and Fig. 2, is a perspective of the article extended as a step ladder.

The design relates to step ladder chairs, and consists of the several distinctive features or form and outline which will be hereinafter more fully set forth.

The device embodying the features of the design comprises two portions A and B each of which is substantially triangular in form, the portion B having an extension of open work of concavo-convex contour transversely throughout its longitudinal length to form a back and arranged at a rearward oblique angle. The other portion A is supplied with supports a, and the portion B is also provided with supports b within its triangular contour. The two portions A and B when arranged as a chair have contiguous parallel plane pieces to form a seat, the front and side edges of which extend beyond lower adjacent portions and are beveled in curved outlines, the rear-most of said pieces D being a part of the portion B. Under the front of the portion A is a straight strip d extending from one support a to the other and having its under edge of compound curved form, while the said sup-

ports are of themselves composed of a series of irregular and regular exterior ornaments. The upper part of each support a is rectangular and merges into a tapering rounded surface which terminates in a series of circumferential beads. From the said beads, the surface diverges in rounded form to a cylindrical surface and from the latter downwardly and unbroken compound curved surface follows. The extension of the portion B, has a curved strip C thereon with opposite compound curved ends, and also another narrow strip c of curved outline, said strips C and c having surrounded pieces E running from one to the other. That part of the portion B having said extension therefrom is curved slightly in a reverse direction, the median line of the change of direction being established from the point where the surface D engages said portion B. The bottom piece of the portion B is also formed with beveled edges in compound curved outline, and the connecting angles immediately above said piece are in curved lines.

The step pieces of the device have their opposite ends, angular in form. These features of contour form an essentially distinctive design and produce a pleasing appearance.

Having thus described the invention, what is claimed as new is—

The herein described design for a step-ladder chair, as set forth.

In testimony whereof I set my signature in the presence of two witnesses.

FREDERICK H. HERHOLD.
